E. NIEHOFF.

DIVING APPARATUS.

APPLICATION FILED JUNE 7, 1911; RENEWED NOV. 12, 1913.

1,099,814.

Patented June 9, 1914.

UNITED STATES PATENT OFFICE.

ERNEST NIEHOFF, OF ROANOKE, VIRGINIA, ASSIGNOR, BY DIRECT AND MESNE ASSIGNMENTS, TO ROANOKE WRECKING & SALVAGE COMPANY, INC., OF ROANOKE, VIRGINIA.

DIVING APPARATUS.

1,099,814.

Specification of Letters Patent. Patented June 9, 1914.

Application filed June 7, 1911, Serial No. 631,765. Renewed November 12, 1913. Serial No. 800,677.

To all whom it may concern:

Be it known that I, ERNEST NIEHOFF, a citizen of the United States, residing at Roanoke, in the county of Roanoke and State of Virginia, have invented certain new and useful Improvements in Diving Apparatus; and I do hereby declare the following to be a full, clear, and exact description of the invention, such as will enable others skilled in the art to which it appertains to make and use the same.

This invention relates to improvements in diving suits or apparatus, and particularly to improved diving apparatus which will permit a person to operate in extreme depths of water if desired.

The object in view is the arrangement of an improved diving suit or dress arranged to permit the diver to operate in extreme depths of water and use only a small pressure of air while so operating.

A still further object of the invention is the arrangement of a diving suit or apparatus having an inner shell or dress of metal designed to resist high pressure of water, over which dress or shell is arranged a flexible suit having connected therewith a helmet for receiving air under any desired pressure, the helmet and the flexible suit being designed to prevent the entrance of water while the metallic dress is designed to resist the pressure of water.

With these and other objects in view the invention comprises certain novel constructions, combinations, and arrangement of parts as will be hereinafter more fully described and claimed.

In the accompanying drawings: Figure 1 is a side view of an embodiment of the invention, certain parts being shown in section for better illustrating the structure. Fig. 2 is a longitudinal sectional view through a valve. Fig. 3 is a cross section through the valve shown in Fig. 2. Fig. 4 is a longitudinal sectional view through an inlet valve embodying certain features of the invention.

In the use of an ordinary diving dress or apparatus the air which is pumped into the helmet is of higher pressure than the water in which the diver is operating as it is necessary to overcome the water pressure before the vitiated air can escape from the helmet. This necessitates the breathing by the diver of more or less high pressure air according

to the depth of water in which he is working. In order to permit the diver to operate in any depth of water desired a pressure resisting inner suit is provided, the same embodying certain features of the invention. 60 This inner suit is designed to fit from the shoulders down to and including the feet, and is arranged to entirely cover the diver but is not constructed necessarily water tight. The body portion of the inner suit is 65 made comparatively large so as to provide ample space for movement of the diver in the suit, and also to provide space for an ample volume of air. Arranged over this suit are one or more flexible suits, one of 70 which is provided with a helmet constructed sufficiently strong to withstand substantially the same pressure which the inner suit is designed to withstand. The helmet and the outer suit prevent the entrance of water, 75 while the helmet and the inner suit resist the pressure of water so that air may be forced into the helmet under any desired pressure and the vitiated air removed therefrom and exhausted at the surface of the water. 80 When a third suit is provided the same is designed principally to be used in floating the diver either to the surface or to any intermediate point.

In order that the invention may be more 85 clearly understood an embodiment of the same is shown in the accompanying drawings in which—

1 indicates the inner suit which suit is formed with leg portions 2 and body portion 3. Connected with body portion 3 are arm portions 4. The leg and arm portions are formed with a ball and socket arrangement at the joints of any desired or preferred form. The body portion 3 is made 90 sufficiently large for permitting the diver to move his body therein to a considerable extent and to provide space for a considerable volume of air. Positioned over the metal suit 1 is a flexible suit 5 provided with a 95 helmet 6. The suit 5 may be made of canvas and rubber or other material as may be desired, and may be secured to helmet 6 in any desired way. Helmet 6 also is preferably of the usual type of helmets, and is 100 arranged to fit over the head and extend down for a short distance over the body 3. The helmet 6 is provided with an outlet tube 7 and an inlet tube 8. These tubes are arranged to extend to the surface of the 110

water so that tube 8 may receive air from any suitable pump or other supply, and tube 7 may exhaust into the atmosphere. Each of these tubes is constructed of flexible material, but sufficiently strong to resist the pressure of water for a considerable depth without collapsing. Valves 9 and 10 are provided for these tubes as shown more clearly in Figs. 2, 3 and 4. Valve 9 is set or positioned so as to permit the exhaust of air through tube 7. Valve 10 is formed with a stationary casing 17 (Fig. 4) which has formed therein a plurality of apertures 18 designed to register with apertures 19 of the reciprocating sleeve 20 positioned in casing 17. The sleeve 20 is formed with a bottom 21 so that any air pressure entering casing 17 will also enter the sleeve 20 and move the same inward. A spring 22 is provided for resisting the inward movement of sleeve 20 so as to require more or less pressure for causing the apertures 18 and 19 to register. The tension of spring 22 may be controlled and varied by a set screw device or adjusting member 23 connected to the lower end 24 of the casing 17. Under ordinary circumstances where a diver is operating at extreme depths air is supplied to him under ten or fifteen pounds pressure, and spring 22 is therefore set to permit apertures 18 and 19 to register under the desired pressure. If the pressure falls considerably below the desired pressure or rises considerably above the same the registration of the apertures will not take place. This is of extreme advantage whenever it should become necessary for the diver to cut himself loose, that is, cut the tubes 7 and 8 and 14, so that he may come to the surface without delay. The valve 9, however, is preferably of the construction shown in my Patent #650,650 which will freely permit the exhausting of the vitiated air but will act as a check valve and prevent the entrance of any water in case the tube to which it is connected is cut. This is of advantage in that the valve will not admit water into the helmet 6 in case the diver finds it necessary to sever tubes 7 and 8. Valve 9 is formed with a housing 25 which is preferably threaded at 26 in order to be secured to tube 7. Housing or sleeve 25 is formed with a plurality of apertures 27 and an annular offset portion 28. Arranged within the housing or sleeve 25 is a reciprocating valve member 29 formed with a plurality of openings 30 designed to register with or come opposite apertures 27 when a predetermined amount of pressure has been brought to bear on the inner side of the plug 31 which acts as means for closing the end of valve member 29. Connected with the lower end of valve member 29 is a reciprocating bearing member or sleeve 32 against which presses a spring 33. Spring

33 also presses against the annular projection 28 so that the upward or inward movement of valve member 29 is resisted and the valve member 29 is caused to assume the position shown in Fig. 2 when not positively moved therefrom by pressure in helmet 6. By this structure whenever the pressure in helmet 6 is sufficient valve member 29 will be moved longitudinally of housing or sleeve member 25 until openings 30 will come opposite or register with openings 27, whereupon air may escape from helmet 6 into tube 7.

The flexible suit 5 is formed in substantially the same way as the ordinary suit now in use, except possibly slightly larger so as to fit over the dress or suit 1. The arms of the flexible suit 5, of course, fit over the arms 4 of suit 1. The arms 4 of suit 1 extend only to the hands, while the arms of suit 5 extend outward and are formed into gloves or mittens so as to permit the diver to properly use his hands. A clamping member 11 is provided for firmly clamping the wrist of the flexible sleeve with the wrist of the sleeve of arm 4. In this way no part of the body will be subjected to the pressure of the water except the hands which will ordinarily withstand a comparatively high pressure. In addition to the flexible suit 5 a second flexible suit 12 may be provided which extends only from the bottom of the helmet down to and including the feet. This second suit is preferably arranged to fit the feet and legs up to the knees reasonably tight, but from the knees up to the bottom of the helmet suit 12 is made sufficiently large or full for providing a space between the same and flexible suit 5. Suit 12 is formed with an ordinary check valve 13 which will permit the exhausting of air out from between suits 5 and 12 but will not admit water therein. Also connected with suit 12 is a tube 14 having a valve 15 associated therewith which will permit the entrance of air between suits 12 and 15. Valve 15 is constructed similar to valve 10 so that the same opens and closes at each stroke of the piston of the pump. This prevents the entrance of water between suits 5 and 12 in case tube 14 should become cut or broken as the pressure of water will cause only one movement of valve 15 and allow the entrance of only a negligibly small quantity of water. The tubes 7, 8 and 14 are grouped and held together by suitable clamps 16 so that in a certain sense they present only the appearance of a single tube or rope.

The helmet 6 may be provided with a telephone of any desired structure if desired, and the suit may have connected therewith a signal rope if the same should be necessary or desirable. Under ordinary

circumstances the pressure resisting suit 1 is used and suit 5, which will permit the diver to operate at varying depths down to the limit of resistance of suit 5, and helmet 6, which preferably is made to withstand sufficient pressure to permit the diver to operate freely at 200 or 300 feet of water. If for any reason it should be desired to float the diver to the surface, or partially to the surface, air may be inserted through tube 14 into the flexible suit 12 to any desired extent for accomplishing the purpose desired. Any excess of air in suit 12 will, of course, exhaust out valve 13, which air, of course, must be at a higher pressure than the water.

In constructing metal suit 1 the same may be made of solid metal, though preferably it is made of perforated metal for providing a comparatively light pressure resisting armor but one sufficiently strong for the purpose desired. To additionally lighten the armor the metal may be composed of aluminum or partially aluminum if desired.

What I claim is:

1. A diving apparatus comprising a pressure resisting suit formed of a plurality of parts fitted together for permitting a substantially free movement of a person using the suit, a water resisting suit formed with a body of flexible material and a helmet, an inlet tube for supplying air to said helmet, a valve arranged at the juncture of said inlet tube and said helmet for admitting air into said tube under a predetermined pressure, an air escape tube connected with said helmet, and a valve arranged at the juncture of said escape tube and said helmet formed so as to permit the air to escape from said helmet into said tube to prevent anything from entering into said helmet from said tube.

2. A diving apparatus comprising a pres-

sure resisting suit of metal, a water resisting suit formed of flexible material in the body portion and of rigid material at the head portion, said rigid material defining a helmet, means for admitting air into said helmet, a discharge tube for discharging air from said helmet, a valve for regulating the admittance of air into said helmet, a valve for regulating the discharge of air from said helmet, a second flexible suit arranged over said first mentioned flexible suit, said second mentioned flexible suit being formed of water and air resisting material, and an inlet tube for directing air into said second mentioned flexible suit for permitting said second mentioned flexible suit to be inflated independent of the inflation of the helmet and first mentioned flexible suit.

3. A diving apparatus comprising a metallic suit arranged to resist pressure of water and formed so as to extend from the neck down to and including the feet, a second suit formed of a flexible portion, and a helmet being designed to fit over the head and part of the first mentioned suit, and said flexible portion to fit over the remaining part of said first mentioned suit, an air supply tube connected with said helmet, an air exhaust tube connected with said helmet, a third suit of flexible material extending from said helmet, an air supply tube connected with said third suit, and a check valve for permitting the excess air pressure in said third mentioned suit to escape.

In testimony whereof I affix my signature in presence of two witnesses.
